UNITED STATES PATENT OFFICE.

WILLIAM DIXON DENTON AND ROBERT WINSFORD DENTON, OF WELLESLEY,
MASSACHUSETTS.

DESIGN FOR A LOCKET, PENDANT, OR SIMILAR ARTICLE.

No. 39,413.

Specification for Design.

Patented July 14, 1908.

Application filed February 3, 1908. Serial No. 414,131. Term of patent 14 years.

To all whom it may concern:

Be it known that we, WILLIAM DIXON DENTON and ROBERT WINSFORD DENTON, citizens of the United States, residing at Wellesley, in the county of Norfolk and State of Massachusetts, have invented a new, original, and ornamental Design for Locket, Pendants, or Similar Articles, of which the following is a specification, reference being had to the accompanying drawing, illustrative of one embodiment of our design, forming part thereof.

The figure is a plan view of one article of jewelry, namely, a locket or pendant embodying our design.

In the embodiment shown, a mounting of circular form appears, surrounding a field or background, centrally of which field is a butterfly in relief with wings in upfolded or closed position.

We claim:

The ornamental design for a locket, pendant, or similar article as shown.

WILLIAM DIXON DENTON.
ROBERT WINSFORD DENTON.
